CHEST OF DRAWERS

Aaron Donner, Weston, Conn., assignor to
The Lane Company, Inc.

Filed July 10, 1974, Ser. No. 487,379

Term of patent 14 years

Int. Cl. D6—04

U.S. Cl. D6—154

The figure is a front, top and left side perspective view of a chest of drawers showing my new design, the right side being substantially identical to the left.

The rear of the chest is plain and unornamented.

I claim:

The ornamental design for a chest of drawers, as shown and described.
